UNITED STATES PATENT OFFICE.

ALBERT A. WEBER, OF SACRAMENTO, CALIFORNIA, ASSIGNOR OF ONE-THIRD TO
MARK L. BURNS AND ONE-THIRD TO HENRY A. DAVIES, BOTH OF SACRAMENTO,
CALIFORNIA.

OIL AND DUST PROOF JOURNAL-BOX.

1,277,798.

Specification of Letters Patent. Patented Sept. 3, 1918.

Application filed February 10, 1917. Serial No. 147,951.

To all whom it may concern:

Be it known that I, ALBERT A. WEBER, a citizen of the United States, residing at Sacramento, in the county of Sacramento and State of California, have invented certain new and useful Improvements in Oil and Dust Proof Journal-Boxes, of which the following is a specification.

This invention relates to improvements in journal boxes and the principal object is to provide an oil and dust proof box which will thoroughly protect the journal bearing from injury.

Another object of the invention resides in the provision of a novel cover plate and cap for the journal box.

With the above and other objects in view as will become more apparent as the description proceeds, the invention consists in the novel combination and arrangement of parts as will be fully set forth in the following specification, claimed and illustrated in the accompanying drawing, in which,

Figure 1, is a perspective view of a journal box constructed in accordance with this invention,

Fig. 2, is a longitudinal sectional view through Fig. 1,

Fig. 3, is a transverse sectional view through Fig. 1,

Fig. 4 is a perspective view of the cap,

Fig. 5, is a detail perspective view of the extensible filler member, and

Fig. 6, is a detail perspective view of one of the cover elements.

Referring to the drawings by characters of reference, the numeral 1, designates as an entirety the journal box, which comprises a bottom wall 2 having formed along its side edges the side walls 3, which are connected at their upper edge by a top wall 4. The side walls are continued forwardly intermediate their upper and lower edges to form inclined edges, the lowermost of which are connected by a front wall 5. A rear wall 6, is provided and connects the bottom, top and side walls and this rear wall is formed with an elongated vertically extending aperture 7, through which the end of the axle 8 extends. Flanges 9 are formed on the edges of the rear wall and as illustrated the top and bottom flanges, designated by the numeral 9, are slightly offset to form guides for the cover elements which will be more fully hereinafter described. A journal bear-

ing block 11, fits into the box and is hollowed out as at 12, to fit the axle 8, previously mentioned. Suitable straps 13, extend beneath the axle to hold the same in place.

In order to close the upper part of the journal box at the front end thereof, a cap 14, is provided which cap consists of a plate 15, formed with an angularly extending flange 16, arranged along its upper edge. This plate 15, has formed near its lower edge an inclined rib 17, the lower wall of which is adapted to engage the inner face of the upper edge of the front wall 5, when the device is assembled. Vertically extending arms 18, are formed at the ends of the rib 17, and are adapted to engage the inner faces of the forward edges of the side walls 3, while the flange 16, lies on the upper side of the forward edge of the top wall and is provided with a screw receiving opening which registers with a similar threaded opening formed in the top wall. A screw 19, is adapted to fit in the said openings and forms the retaining means for the cap.

The rear end of the box is closed by a cover plate formed in two separate sections, one of which is illustrated in Fig. 5, and in view of the fact that the other section is identical in construction, but one will be shown and described. Each section of the said cover plate consists of a back wall 20, provided at its top and bottom edge with a flange 21, terminating in a right-angularly extending flange 22, which in conjunction with the flange 21, forms a trough shaped structure, into which the offset flanges 9, of the box fit when the device is assembled. One edge of the back wall is formed with a side flange 23, which connects the end flanges 21, so that the whole forms a substantially box shaped structure. The edge of the back wall 20, opposite that on which the flange 23, is formed is provided with a recess, which is preferably slightly elongated to allow the axle a slight vertical movement in the journal box.

In order to completely close the box and render the same dust tight around the point where the axle enters the same, a dust tight gasket is provided, which is best illustrated in Fig. 5, and consists of two plates 24 and 25, each of which is provided with flanges 26, which as shown are of less thickness than the plates. The flanges extend beyond the adjacent ends of the plates and form

guides, so that the plates may be slid relatively to each other in longitudinal alignment, and any danger of the same becoming displaced will be avoided. The end of each 5 plate is formed with an arcuate recess and when the plates are assembled and in place it will be readily recognized that a substantially circular recess for the reception of the axle is provided, which is so arranged that 10 the walls thereof may give vertically and yet remain at all times in contact with the said axle. One of the plates, namely that designated by the numeral 24, is formed with a longitudinal recess 27, while the other 15 is provided with the leaf springs 28. A suitable coiled spring 29, is seated in the recess 27, and tends to normally force the plate 24, upwardly against the axle in order to assure a tight fit between the parts.

20. In use it will be seen that the device is assembled in the manner shown in Figs. 2 and 3, so that the plates 24 and 25 forming the gasket, are positioned between the back wall 6, and the cover plate. When it is desired to gain entrance to the front end of the 25 box, the screw 19, is removed and the cap may then be easily removed. In order that the rear end of the box may be opened, it is necessary to slide the cover plate sections 30 off laterally, at which time the gasket will be exposed and may be readily removed from within the box, thus leaving the same entirely open. Due to the resiliency of the fit of the gasket against the axle it will be 35 readily understood that no special care is necessary in re-assembling the device except to see that the parts are properly related and it is evident that the device is easily accessible, thus facilitating the making of repairs.

While in the foregoing there has been

described, and shown a particular type of this invention it is to be understood that certain minor changes in the details of construction, combination and arrangement of parts may be resorted to without departing from the spirit of the invention as claimed.

What is claimed is:-

1. In a journal box, a gasket comprising a pair of plates, each having an axle receiving recess formed in one end, the plates fitting together so as to cause the recesses to form an opening through which the axle fits, means to force one of the plates against the axle and means to yieldably hold the plates together. 50
2. In a journal box, a gasket comprising a pair of plates, flanges on the plates, the flanges being extended beyond the ends of the plates, the ends of the plates beyond 55 which the flanges extend being recessed to receive an axle, the plates being slideable on the flanges with relation to each other, means to force one of the plates against the axle and means to yieldably hold the flanges together. 60
3. In a journal box, a box having an opening formed in its rear wall, flanges formed on the edges of the rear wall, a cap comprising a pair of plates each having a recess 70 formed therein, flanges on the plate forming troughs to receive the flanges on the rear wall of the box, a gasket comprising a pair of plates, each having a recess in one end adapted to fit around an axle, guide flanges 75 formed on each plate whereby the plates may slide longitudinally, means to yieldably hold one of the plates against the axle and means to hold the plates yieldably against each other and between the cap and rear 80 wall.

ALBERT A. WEBER.
